ATTORNEY

UNITED STATES PATENT OFFICE.

GEORGE C. L. TISCH, OF ELIZABETH, NEW JERSEY.

COMBINATION PLATE AND THREAD GUIDE.

1,422,799.

Specification of Letters Patent.

Patented July 11, 1922.

Application filed July 29, 1920. Serial No. 399,793.

To all whom it may concern:

Be it known that I, GEORGE C. L. TISCH, a citizen of the United States, and a resident of Elizabeth, in the county of Union and State of New Jersey, have invented a new and useful Combination Plate and Thread Guide, of which the following is a full, clear, and exact description.

This invention relates to attachments for the thread bar of a knitting machine of the type shown in Patent No. 457,265, issued August 4, 1891, to Julius Freelloehr and Louis Tisch and has for an object to provide an improved construction in the nature of a thread guide wherein the tube may be applied and removed quickly.

Another object of the invention is to provide a thread guide designed to carry one or more tubes and be held in place by a single clamping member.

A further object of the invention is to provide an improved plate and thread guide wherein the plate is formed of lugs for assisting in holding a tube in place when clamped to the plate.

In the accompanying drawing:

Figure 1 is a view showing a thread bar associated with a jacquard wheel and a plate and thread guide embodying the invention. Figure 2 is a front view of the plate and guide member shown in Figure 1.

Figure 3 is a sectional view through Figure 2 on line 3—3.

Figure 4 is an edge view of the structure shown in Figure 2 except one of the tubes is shown as a left.

Figure 5 is a perspective view of a support and a pair of tubes embodying certain features of the invention.

Figure 6 is a perspective view of a second form of support and tube.

Referring to the accompanying drawing by numerals, 1 indicates what may be termed a jacquard wheel carrying the usual pins 2 for actuating the thread bars 3. The thread bars 3 are the usual construction used in certain forms of knitting machines (see Patent No. 457,265) and designed to carry a number of plates 4. Each of these plates 4

is provided with a notch or slot 5 for accommodating the clamping screw 6 as shown in Figure 2. The plate 4 is intended for use with tube supports and heretofore the tubes have been arranged with a separate

stem for each tube and a separate clamping

member for each tube. In the present invention the plate 4 is made somewhat different, namely with a pair of bosses or extending lugs 7 and a flange 8 provided with a pair of notches 9 in which the U-shaped tube supporting members 10 and 11 fit as well as a threaded aperture 7'. These supporting members have connected therewith tubes or thread guiding means 12 which may be of any size and also may be on either side of the members 10 and 11. As shown in Figure 6 the member 11 forms a complete U-shaped structure, but the short leg of the hook is of sufficient length to fit into one of the notches 9 while the curved end fits over one of the lugs 7. This positively locks the supporting member in place when the clamping screw 13 is tightened; this screw being provided with a head overlapping the legs of the U-shaped member 10. A clamping screw 14 similar to the clamping screw 13 is provided for the member 10 so that there is only arranged two screws for two supporting members, and as shown in Figure 2 three tubes are supported by the two supporting members, but if desired only two tubes may be supported or four tubes, also the tubes may be made large or small as shown in Figures 5 and 6, and as indicated in Figure 4 the tubes could be on opposite sides of either of the supporting members, and in fact the arrangement of the tubes in respect to the supporting members may be right and left throughout the entire series. As shown in Figure 5 there are two rights while in Figure 6 there is one right. If desired the structure in Figure 5 could be two lefts or one right and one left, while the structure shown in Figure 6 could be a left instead of a right as indicated. The tubes 12 are preferably arranged or positioned so that their longitudinal axes will be parallel to the longitudinal axis of the legs of the supporting member 10. As shown in Figure 2, each of the supporting members 10 fit over a lug 7 and into suitable notches 9 in flange 8 so that when the clamping screws 13 and 14 are tightened, the supporting member will be rigidly held in place.

In applying or removing the thread guide it is merely necessary to remove the screws 13 and 14 and bodily disconnect the guides. The various guides are replaced by a reverse action.

In using the attachment the tubes 12 guide

the threads from the spools to the needles in a well known manner as illustrated in the heretofore mentioned patent.

What I claim is:

- 5 1. In a thread guide, a plate provided with threaded openings, spaced lugs above the openings, and a transverse flange below the opening and formed with pairs of notches, each pair of notches being so positioned that the central axis therebetween will be in line with a lug and opening of the plate, and tube-supporting members each having a U-shaped end engaging a lug of the plate with the legs thereof seated in a 10 pair of the notches of the flange.
- 15 2. In a thread guide, a plate provided with a transverse notched flange, a threaded opening above the flange and a lug above the
- opening, a threaded guide supporting member seated in the notched flange and having 20 a U-shaped end engaging the lug, and a screw screwing into the threaded opening of the plate and engaging the supporting member.
- 25 3. In a threaded guide, a plate having a transverse flange provided with a plurality of notches, a threaded opening above the flange, and a lug above the opening, a thread guide supporting member having a U-shaped end, the U-shaped end engaging the lug and 30 the legs thereof seating in the notches of the flange, and a screw screwing into the opening of the plate and engaging the legs of the supporting member.

GEORGE C. L. TISCH.
